UNITED STATES PATENT OFFICE.

JAMES C. KIMSEY, OF LITTLE ROCK, ARKANSAS, ASSIGNOR TO THE
PHILADELPHIA CAMERA COMPANY, LIMITED, OF PHILADELPHIA,
PENNSYLVANIA.

PHOTOGRAPHIC-PLATE CARRYING AND TRANSFERRING CASE.

SPECIFICATION forming part of Letters Patent No. 607,052, dated July 12, 1898.

Application filed September 2, 1897. Serial No. 650,373. (No model.)

To all whom it may concern:

Be it known that I, JAMES C. KIMSEY, a citizen of the United States, residing at Little Rock, in the county of Pulaski and State of Arkansas, have invented certain new and useful Improvements in Photographic-Plate Carrying and Transferring Cases; and I do hereby declare the following to be a full, clear, and exact description of the invention, such as will enable others skilled in the art to which it appertains to make and use the same.

This invention is an improvement in carrying-cases for photographic dry-plates, the object of the same being to provide an apparatus which will carry a large number of plates approximately one upon the other and permit of their being transferred to an ordinary plate-holder without risk of exposure, provision being made for unloading the holder after exposure of the plates.

In the art of photography numerous attempts have been made, with more or less success, to provide a magazine-camera using the dry-plates and including mechanism for bringing them into place, successively, for exposure, such contrivances making the proper adjustment of the camera very difficult of accomplishment and not giving the satisfaction had by the ordinary removable plate-holder. Appreciating the many advantages of the plate-holder and also its disadvantage of limited capacity in carrying plates, I have devised a case or box in which a number of plates can be closely packed and dropped one at a time into the plate-holder, which is slipped into place for the purpose, said plate-holder being reversed in filling the same, the particular construction and arrangement of the parts or instrumentalities entirely preventing the slightest exposure of a plate during its transfer from the storage-compartment to the plate-holder or during the unloading of the latter.

The invention anticipates an apparatus by which but a single plate-holder is needed in taking a large number of exposures, the loading and unloading of said plate-holder not requiring the services of a dark room or even so much as a cover for the box, the light being at all times entirely excluded from the

compartment, which contains both the unexposed and exposed plates.

The following specification will give a detail description of the parts constituting the invention, and what I consider to be novel in the art will be more particularly set forth in the appended claims.

In the accompanying drawings, which form a part of this specification, Figure 1 is a front elevation of a carrying and transferring case for photographic dry-plates constructed in accordance with my invention. Fig. 2 is a transverse sectional view of Fig. 1. Fig. 3 is a similar view on the line 3 3 of Fig. 2. Fig. 4 is an enlarged detail view of one of the spring plates or supports for the photographic plates. Fig. 5 is a detail plan view of a backing for the photographic plates to slightly separate them when placed one upon the other. Fig. 6 is a view showing the backing applied. Fig. 7 is a transverse sectional view through Fig. 6. Fig. 8 is a detail sectional view illustrating an attachment to the plate-holder for wedging the plates therein.

In carrying out my invention a rectangular box or casing A is constructed, presenting a compartment of the proper dimensions horizontally to suit the size of the photographic plates which it is designed to contain, said box being painted black interiorly and preferably covered to totally exclude light, which might otherwise enter at the joints. The upper and lower ends of this box are formed by hinged covers or lids a a', held in place by hasps b, engaging staples b', or by other suitable fastening devices. In the front of this box, at or near the upper and lower ends thereof, are transverse openings c and c', respectively, adjoining which, toward the center of the box, are slits d d', extending parallel with said openings, the slits communicating at their ends with grooves d² in the sides and connecting with a corresponding groove d³ in the back. The slits receive metal plates or slides, the edges of which fit within the grooves, and said slides serve to exclude from the center or intermediate portion of the compartment what light may enter through the openings c and c'.

The interior of the box or casing A is pro-

vided near its lower end with shoulders $e e$ and e' , forming surfaces against which bear the photographic-plate holder, hereinafter described, said plate-holder being held tightly 5 against the shoulders by flat springs ff and the front of the box rabbeted, as shown at a^2 , to receive the transverse ridge usually formed on said plate-holder. It will be here noted that when the plate-holder is in place the 10 light will be excluded thereby from the central portion of the compartment and permit the withdrawal of the slide D' in dropping a photographic plate into the plate-holder, as hereinafter explained. The box is also pro- 15 vided at its upper end with shoulders gg and g' on a line with the lower edge of the upper opening c , springs $f' f'$ being also provided at this point to force the plate-holder against said shoulders.

20 In the inner side of the front and back of the box or casing, beginning at a point slightly above the lower slide D' , are formed tapered recesses a^3 , in which are located spring-metal plates $II\ II$, attached to the box at their upper ends to leave their lower ends free, said lower ends being turned at right angles to present blades h , which enter between the photographic plates (designated by the letter S) and serve to support them within the box. 25

30 These plates are operated by rods h' , which extend through the box and terminate in knobs h^2 . The blades of the plates are located above the slide D' a distance slightly greater than the thickness of the photographic 35 plates in order that when said spring-plates are moved into the recesses to permit the photographic plates to drop upon the slide and then released the blades will enter between the lower photographic plate and the one immediately above.

For the purpose of separating the photographic plates and permit the blades to enter between them each photographic plate is provided with a backing T , consisting of a sheet 45 of paper or other material having strips t at its side edges to give additional thickness, while the corners are extended to form flaps t' , those at one end of the sheet being folded and pasted to form pockets and those at the 50 other end left free to be folded over the corners of the plate after it has been placed in engagement with said backing, the last-mentioned flaps having adhesive material applied to facilitate pasting the ends upon the sheet. 55 This backing leaves the front side of the photographic plate entirely exposed, with the exception of the corners, which are covered by the pockets. The opposite ends of the backing are cut away, as shown, so as not to interfere with the blades.

The plate-holder S' is of the double-plate-holder pattern of the ordinary construction, having a partition-plate s and the usual slides $s' s'$, being modified in the particular to have 60 the plates inserted from the front after the slide is withdrawn, and in order to hold the plate in place one side of the holder is pro-

vided with a wedge-shaped recess, in which is located a wedge u , having an operating-rod u' extending through a longitudinal opening 70 in the holder and bent upon itself to enter a second opening therein, presenting a looped handle. By pushing upon the rod the wedge engages one edge of the plate and holds it securely in place. 75

From the foregoing description, in connection with the accompanying drawings, the construction and operation of my improved photographic-plate carrying and transferring case will be readily apparent, for after the unexposed plates have been placed in the compartment between the slides D and D' , resting upon the blades of the spring-plates $II\ II$, said spring-plates are manipulated to drop a photographic plate upon the slide D' , and the plate-holder being inserted in the lower opening c' said slide is withdrawn to permit the plate to drop into the plate-holder, it being understood, of course, that the upper slide of said plate-holder is first withdrawn. The slide is then inserted into the plate-holder, and after pushing in the slide D' the plate-holder is reversed and the operation repeated to fill said plate-holder. In disposing of exposed plates the plate-holder is inserted in the upper opening, 90 the lower slide thereof withdrawn, dropping the plate upon the upper slide D , which is then withdrawn to drop the plate into the compartment above the unexposed plates, the exposed and unexposed plates being separated by a follower w , which is preferably of a thickness to be engaged by the spring-plates when resting upon the lower slide D' , thus denoting when all of the unexposed plates have been removed, as in the operation of 95 filling the plate-holder it is reversed in the upper opening in unloading the same, care 100 being taken to have the slide D in place when removing the plate-holder. 105

The apparatus described forms a simple 110 and effective arrangement for loading and unloading photographic-plate holders, and it will be particularly noted that the full capacity of the compartment between the slides is utilized, the plates being removed from below, exposed, and then placed on top, the spaces employed for inserting the plate-holder being comparatively small. By the use of 115 this apparatus the photographer can load and unload his plate-holder without requiring a 120 dark room, and can therefore carry a quantity of plates in a more compact form and at less expense than by the usual method of carrying a number of plate-holders.

The photographic plates are placed within 125 the case through the opening covered by the hinged top and withdrawn or removed by turning the box or case upside down. This would of course dispense with the necessity of having the bottom hinged. 130

Having thus described my invention, what I claim as new, and desire to secure by Letters Patent, is—

1. A carrying and transferring case for pho-

tographic dry-plates, comprising a box enlarged interiorly at each end forming shoulders surrounding three sides of the interior, the front of the box having transverse openings at its upper and lower ends communicating with the enlarged spaces in said box, slides located adjoining the upper and lower shoulders, respectively, and forming a central storage-compartment, spring-plates secured at their upper ends within the box and having each an inturned blade located a certain distance above the lower slide, and rods extending from said plates directly through the sides of the box; the parts being constructed and arranged to receive an ordinary plate-holder passed into the enlarged spaces in the ends of the box through the openings in the front thereof, as shown and described.

2. A carrying and transferring case for photographic dry-plates, comprising a box having transverse openings through one side adjoining the top and bottom boards, shoulders surrounding the interior of the box on a line with the openings, flat springs secured to the inner sides of the top and bottom of the box and projected toward the shoulders; together with slides forming horizontal partitions adjoining the transverse openings, spring-plates attached to inner sides of the box and having inturned blades, and rods projecting from said blades through openings therefor in the

sides of the box; the device being adapted for use in connection with an ordinary plate-holder, as herein shown and described.

3. A carrying and transferring case for photographic plates, comprising a box the top and bottom of which are hinged to the body, said box being enlarged interiorly at each end forming shoulders surrounding three sides of the interior while the front of the box is provided with transverse openings communicating with the enlarged spaces at the ends of said box, slides located adjoining the upper and lower shoulders, respectively, and forming a central storage-compartment, spring-plates secured within recesses in the box and provided at their free ends with inturned blades located a certain distance above the lower slide, and operating rods extending from the center of said plates directly through the sides of the box; the parts being constructed and arranged to receive an ordinary plate-holder passed into the enlarged spaces in the ends of the box through openings in the front thereof, as shown and described.

In testimony whereof I affix my signature in presence of two witnesses.

JAMES C. KIMSEY.
